(57) **CLAIM**

The ornamental design for an umbrella shaft and joint, as shown and described.

DESCRIPTION

FIG. 1 is a rear perspective view of my new design for an umbrella shaft and joint with a locking sleeve in a locked position to maintain the shaft and joint in a use position, and wherein a canopy portion of an umbrella and a chair are illustrated in broken lines for environmental purposes only and not forming a part of the claimed design;

FIG. 2 is a rear perspective view thereof, with the locking sleeve in an unlocked position, but with the shaft and joint still illustrated in a use position;

FIG. 3 is a front elevational view thereof, with the locking sleeve in an unlocked position, but with the shaft and joint still illustrated in a use position;

FIG. 4 is a right side elevational view thereof, with the locking sleeve in a locked position and with the shaft and joint illustrated in a use position;

FIG. 5 is a left side elevational view thereof, with the locking sleeve in an unlocked position, but with the shaft and joint still illustrated in a use position;

FIG. 6 is a bottom view thereof;

FIG. 7 is a top view thereof;

FIG. 8 is a rear elevational view thereof, with the locking sleeve in an unlocked position and the shaft and joint in a non-use or stored position; and,

FIG. 9 is a right side elevational view thereof, with the locking sleeve in an unlocked position and the shaft and joint in a non-use or stored position.

The broken lines shown in the drawings are for illustrative purposes only and form no part of the claimed design.
